UNITED STATES PATENT OFFICE

MAX ALEX, OF ALHAMBRA, CALIFORNIA, ASSIGNOR TO YORK WATER CORPORATION,
LTD., A CORPORATION OF NEVADA

DESIGN FOR A STAND FOR BOTTLED WATER OR THE LIKE

Application filed January 16, 1933. Serial No. 46,856. Term of patent 14 years.

To all whom it may concern:

Be it known that I, MAX ALEX, a citizen of Germany, who has declared his intention of becoming a citizen of the United States, residing at Alhambra, in the county of Los Angeles and State of California, have invented a new, original, and ornamental Design for Stand for Bottled Water or the like, of which the following is a specification, reference being had to the accompanying drawing, forming part thereof.

In the drawing,
Fig. 1 is a front perspective view;
Fig. 2 is a side elevation; and
Fig. 3 is a plan view of a stand for bottled water showing my new design.

I claim:

The ornamental design for a stand for bottled water or the like, as shown.

MAX ALEX.
